UNITED STATES PATENT OFFICE.

WILLIAM T. RUTLEDGE, OF SANTA ANA, CALIFORNIA.

HOSE CLAMP.

Application filed December 10, 1923. Serial No. 679,621.

To all whom it may concern:

Be it known that I, WILLIAM T. RUTLEDGE, a citizen of the United States, residing at Santa Ana, in the county of Orange and 5 State of California, have invented new and useful Improvements in Hose Clamps, of which the following is a specification.

This invention relates to clamping devices and it has particular application in the 10 clamping of a hose or tube to a nipple, and is especially valuable for such use when applied to automobile engines.

An object of this invention is to provide a clamp of the above character which may 15 be formed of wire and so constructed as to avoid gaps which would lead to pinching and consequent injury of the hose.

Another object is to provide a wire hose clamp which may be made from a single 20 piece of wire, simple in structure, economical, and efficient.

A further object of my present invention is to provide a clamp which contains fastening means as an integral part of itself there- 25 by avoiding the use of an extra part such as a nut and bolt as fastening means.

Still another object of this invention is to provide an arrangement in a wire hose clamp which will avoid any binding action during 30 the adjustment of the clamp.

Other objects may be perceived from a reading of the following specification.

In carrying out my invention I employ a single length of wire bent into a ring form 35 generally, but with one or more other bends of a peculiar nature which make the device effective. My device will be more readily understood by reading the specification in connection with the accompanying drawings, 40 in which—

Figure 1 is a perspective view illustrating the clamp as formed with a double hose-engaging ring or annulus.

Figure 2 is a perspective view of a modified form of this invention.

Figure 3 is a perspective view of another modified form of the invention showing the clamp as formed of a single hose-enclosing ring or annulus.

50 Referring now to Figure 1, it will be seen that for some distance from one end of the wire there is a straight portion 5 forming a tongue. At the inner end of the tongue 5 the wire is bent upward at 6 and downward at 7 forming a curved bend or hump 8 transversely of the tongue 5, the inner radius

of curvature of the hump being substantially the same as the radius of the wire used.

The wire is again bent at 9 and the following portion bent on a circle making an open coil or ring 10, after which it is bent upwards at 11 and then brought into the horizontal plane at 12, and is made to pass transversely over the tongue 5, thus making a 60 cross bar 13 in alignment with the hump 8. At 14 the wire is bent downward and at 15 is bent to the right and subsequently turned on a circle to form an open ring or coil 17, the plane of which is substantially parallel 65 to that of the coil 10. At 19 the wire is bent vertically upwards, then crossed over tongue 5 and downward at 20 and disposed between tongue 5 and coil 10, forming a 70 curved bend or hump 21, the under curve 75 of which engages a section of the tongue 5. At point 23 the wire is bent into the horizontal plane and from that point to the end of the wire constitutes a straight tongue 25 which passes between the tongue 5 and 80 the loop 10, under the cross bar 13 and engages the hump 8 on the lower curve of the latter.

In using the device shown in Figure 1 the device is slipped over a hose or tube. 85 The device may then be tightened to the desired degree by applying opposing forces on the outer sides of humps 8 and 21 with a pincers, for example, whereupon the tongues 5 and 25 move through the humps in opposite directions and are guided thereby. 90 After the device has been adjusted the adjustment may be made secure by bending the tongues 5 and 25 partially around the outer leg of the hump by which each is 95 engaged.

Passing now to Figure 2, it will be seen that the clamp, according to this modification, has a hook 28 formed on a tongue 29 of the wire adjacent to it. The wire is 100 turned in a clockwise direction on a circle to form a ring or coil 31, at the end 32 of which the wire is turned upwards and then bent to form a hump 33 passing transversely over, and in contact with, a portion of the 105 coil 31. Adjacent to the hump 33, a hump 34 is formed, at the end of which the wire is again bent in a clockwise direction on a circle to form a coil or ring 35, the wire passing under the hump 34 and being 110 engaged thereby and extending to the right of the hump for some distance to form a

tongue 36, the end portion 37 of which is doubled back on part of the tongue 36, forming a hooked tongue. Formed in the coils 31 and 35, in spaced relation to the humps 33 and 34, are humps 38 and 38', respectively. In adjusting the device shown in Figure 2 it is slipped over the tube or hose and may then be tightened by pulling the hooked tongues 29 and 36 outwardly 10 from the coil until the desired tension is attained, or the device may be tightened to the desired degree by applying opposing forces on the outer sides of the humps 38 and 38', as with pincers, in the same manner 15 as in applying the device, shown in Figure 1. The device may then be locked by bending the tongues 29 and 36, respectively, partially around the outer legs of humps 33 and 34.

20 Referring now to Figure 3, it will be seen that a single length of wire has an end portion 39 doubled back on a part of the tongue 40, the continuation of which is formed into a ring 41. At 42 the wire is bent upward 25 and then curved over the tongue 40 and in contact therewith to form a hump 43. The ring 41 is formed with a hump 44 spaced from the hump 43. In fastening this device the hump 43 may be held in place and the 30 tongue 40 pulled outwardly from the coil until the desired tension is attained, or the humps 43 and 44 may be drawn together by means of pincers or the like. The clamp

may then be locked by bending the tongue 40 partially around any portion of the 35 hump 43.

While I have described my invention in several of its preferred forms, I do not wish to be limited by the constructions shown, but I desire that it be understood that my invention is limited in scope only by the appended claims.

I claim—

1. A hose clamp comprising a single 45 length of wire bent to form at least one ring and at least one hump and having at least one hooked tongue formed by an end portion of said wire, said tongue being engaged by the inner curve of said hump.

2. A hose clamp comprising a single 50 length of wire bent to form a ring and a hump and having a hooked tongue formed by an end portion of said wire, said tongue being engaged by the inner curve of said hump and adapted to be wrapped at least 55 partially around said hump.

3. A hose clamp comprising a single 60 length of wire having end portions forming tongues, a hump adjacent the inner ends of said tongues, said humps engaging said tongues, a portion of the wire intermediate said humps being wound into a plurality of coils having parallel planes and disposed on opposite sides of said tongues, and connected by a bar passing between said humps.

WILLIAM T. RUTLEDGE.
